PHARMACEUTICAL TABLET

Edwin F. Roberts, Stamford, Conn., assignor to
Ives Laboratories, Inc., New York, N.Y.

Filed Dec. 16, 1969, Ser. No. 20,729

Term of patent 14 years

Int. Cl. D28—01; D1—02
U.S. Cl. D16—3

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a top plan view of a pharmaceutical tablet embodying my new design;

FIG. 2 is a bottom plan view thereof;

FIG. 3 is a side elevation as seen at right angle to FIG. 1;

FIG. 4 is another side elevation as seen at right angle to FIG. 3;

FIG. 5 is a top plan view of a modified embodiment of the form illustrated in FIG. 1;

FIG. 6 is a side elevation of the tablet of FIG. 5 as seen at right angle to FIG. 5, the undisclosed bottom portion of the tablet being identical to FIG. 2, and FIG. 4 being representative of the side elevation at right angle to FIG. 6;

FIG. 7 is a top plan view of a further modified embodiment of the form illustrated in FIG. 1;

FIG. 8 is a bottom plan view thereof;

FIG. 9 is a side elevation as seen at right angle to FIG. 7;

FIG. 10 is another side elevation as seen at right angle to FIG. 9;

FIG. 11 is a top plan view of a still further modified embodiment of the form illustrated in FIG. 1; and

FIG. 12 is a side elevation thereof at right angle to FIG. 11, FIG. 8 serving as a bottom plan view and FIG. 10 as a side elevation as seen at right angle to FIG. 12.

I claim:

The ornamental design for a pharmaceutical tablet, as shown.
